Des. 196,246
Patented Sept. 10, 1963

196,246

TOY GUN OR THE LIKE

Irving J. Halpern, Pittsburgh, Pa., and Henry W. Stan,
Chicago, Ill., assignors to J. Halpern Company, Pitts-
burgh, Pa., a partnership

Filed Apr. 2, 1963, Ser. No. 74,265

Term of patent 7 years

(Cl. D34—15)

Fig. 4

FIGURE 1 is a side view of a toy gun showing our new design; the side opposite being substantially similar thereto. The broken line showing of suction darts is for purposes of illustration only;

FIGURE 2 is a front elevational view of the toy gun as seen in the direction of II—II;

FIGURE 3 is a rear elevational view thereof as seen in the direction of III—III; and

FIGURE 4 is a top plan view as seen in the direction of IV—IV.

We claim:

The ornamental design for a toy gun or the like, substantially as shown and described.
